UNITED STATES PATENT OFFICE.

JOSEPH BLOCK, OF NEW YORK, N. Y.

DESIGN FOR A TWO-LIGHT CEILING FIXTURE.

Application filed February 5, 1929. Serial No. 29,946. Term of patent 3½ years.

To all whom it may concern:

Be it known that I, JOSEPH BLOCK, a citizen of the United States, residing in the borough of Manhattan, in the city, county, and State of New York, have invented a new, original, and ornamental Design for a Two-Light Ceiling Fixture, of which the following is a specification, reference being had to the accompanying drawing, forming part thereof.

In the drawing:

Fig. 2 a side elevation, and

Fig. 3 an end elevation of a two-light ceiling fixture showing my new design.

I claim:

The ornamental design for a two-light ceiling fixture as shown.

JOSEPH BLOCK.
